Patented Jan. 3, 1922.

FIG. 1.

FIG. 2.

Fig. 3.

Inventor

George E. Whitside
Edwin H. Harry ^{Attorney}

UNITED STATES PATENT OFFICE.

GEORGE E. WHITESIDE, OF EAST POINT, GEORGIA.

DEMOUNTABLE RIM.

1,402,556.

Specification of Letters Patent.

Patented Jan. 3, 1922.

Application filed July 23, 1920. Serial No. 398,599.

To all whom it may concern:

Be it known that I, GEORGE E. WHITESIDE, a citizen of the United States, residing at East Point, in the county of Fulton and 5 State of Georgia, have invented certain new and useful Improvements in Demountable Rims, of which the following is a specification, reference being had therein to the accompanying drawing.

10 This invention comprises a demountable rim. While its application is unrestricted, it is especially adapted for use in connection with the wheels and tires of motor and the like vehicles.

15 It is contemplated among the objects of the invention to provide a rim of this character which will be "standard" in the sense that it may be used with and fit any of the felloes or wheels at present in extensive use 20 without notching or otherwise changing their construction in order to conform to the rim.

Other objects within the scope of the invention are to provide a rim made in several sections and interconnected so that it may be 25 readily collapsed and assembled; quickly applied to tire casings without the aid of special tools or the aid of skilled labor; which will have a minimum number of parts designed to be constructed and assembled in 30 accordance with the most approved manufacturing methods, and which will, in a word, comprise a simple and practical device for these purposes.

Still other objects are to produce an improved form of interlocking between the 35 edges of the rim at the point of fastening whereby any movement in either an axial or radial direction is prevented when the parts are locked, and wherein a locking device is 40 provided with means for positively positioning the ends of the sections when locking and positively moving one out of alignment with the other when unlocking both movements being accomplished without the aid 45 of additional tools.

Other objects and advantages will in part be apparent and in part be brought out more fully in the description which follows.

A drawing illustrating an embodiment of 50 the invention is hereto appended, the following views being shown:

Fig. 1 is a view in side elevation of the device in assembled position, portions being shown in section;

55 Fig. 2 is a view in perspective showing in detail a form of locking device;

Fig. 3 is a view in longitudinal section through a portion of the device; and

Fig. 4 is a view in bottom plan of a fragmentary detail illustrating a locked arrangement of the meeting ends of the sections. 60

In these views, 1, 2 and 3 designate sections of a demountable rim of the usual channel-shaped variety. Section 2 is, at its opposite extremities, connected to sections 1 and 65 3, respectively. The means here shown comprise a knuckle 4, formed by folding back a flap formed on the end of one of the sections and spot welding it to the portion of the section with which it contacts. Two 70 flaps are generally similarly formed on the part which is to be connected, so that when assembled there will be an eye extending through the aligned flaps and within which a pin or the like 5 may be inserted. This 75 constitutes a hinge joint between the sections, the portions of which are formed directly by stamping and bending a portion of the sections themselves, and the folding back of the flaps and spot welding them to form 80 the hinges eliminates the use of rivets, or other securing means, and insures a composite structure with no additional parts to become loose and rattle.

The other ends of sections 1 and 3 are 85 adapted to be secured together in a manner which will insure against displacement in a radial or axial direction and prevent circumferential expansion. To this end, the underneath portion of the channel sections is provided with corrugations or notches 6 (Fig. 4), 90 which are preferably in the form of projections on one part and corresponding depressions in the coacting part. The arrangement here shown comprises projections on the end 95 of section 1 coacting with corresponding depressions in the end of section 3. When assembled as shown in Fig. 4, the parts will be locked against movement in an axial direction or from side to side on a wheel-felloe. 100

Means are also provided for positively locking the ends of connected sections 1 and 3 against radial movement when they are in locked position; and as here shown, such 105 means comprise corrugations or notches 7 on the sides of the sections. These, as just described, also have the form of lugs or projections on one section coacting with and fitting into correspondingly shaped depressions on the other section, so that when assembled, as shown in Fig. 1, they will be 110

prevented from relative movement in a radial direction.

A combined locking instrumentality and section-separating means is associated with 5 the free or outer ends of sections 1 and 3, just described, and, as here shown, include an actuating lever 8 pivotally secured at one 10 end to the end of one of the sections. The manner of connecting is by means of a pin 9 which passes through an opening 10 in the end of the lever and through eyes formed on a knuckle 11 on the end of the section to which it is secured.

In connection with this line there is provided 15 a means of first imparting to the abutting ends of the section when assembled a circumferential movement to disengage the corrugated portions 7 of the sections. This is done at the initial movement of the 20 lever, and, as here shown, is effected by means of a cam 12 having a notch 13 cut across its face, leaving ribs or projections 14 and 15 along the face thereof, one of 25 which, 14, normally engages an end portion of one of the sections when closed. Movement of the lever to the position shown in Fig. 3 forces the ends of the sections apart and initiates a relative movement of the sections radially. This radial movement is 30 started by projection 14 and completed by the other projection 15 on the cam, the latter being adapted to engage the inner portion of the section against which it is bearing and positively move it out of alignment 35 with the end of the next abutting section. When the end has passed out of alignment the entire sections 1 and 3 may be swung on their pivots inwardly for dismounting. To facilitate the initial movement 40 of the lever, it is provided at its opposite end with under-cut portions 16 for the insertion of a wedge as the pressure of projection 14 against the end of section 1 normally holds the lever flat against the under 45 side of the rim. A pin 17 is also provided in the outer end of lever 8 and fits in an opening in the rim when the lever is in closed position. This locks the sections against circumferential movement.

50 To give an initial spreading movement to the ends of sections 1 and 3 when assembling, lever 8 is provided at a point near its pivotal connection to the end of section 2 with a notch 18. This notch engages the 55 end edge of section 1 before it comes in contact with projection 14 on cam 12 and initiates the spreading of the sections. Continued movement of lever 8 to open position forces the end out of the notch and into 60 contact with projection 14 in the cam face.

The hinges and lever are of approximately equal thickness and constitute bearing points for the rim or the felloe. The rim is also provided with a valve guide and 65 retainer 19, here shown punch drawn from

the metal of the rim, the arrangement being such that when inwardly projecting portion 20 is inserted in a hole in the felloe provided for this purpose, it also prevents relative circumferential movement between the felloe 70 and the rim.

What I claim is:

1. A demountable rim comprising a plurality of sections connected together for swinging movement inwardly; and means 75 for locking the sections in assembled position as a complete rim, said means including a lever pivotally mounted on an end portion of one of the sections, and a cam portion in the lever, said cam being provided with a notch adapted to receive an end portion of a section when in locked position.

2. A demountable rim comprising a plurality of sections connected together for 85 swinging movement inwardly; and means for locking the sections in assembled position as a complete rim, said means including a lever pivotally mounted on an end portion of one of the sections, a cam portion 90 in the lever, said cam being provided with a notch adapted to receive an end portion of a section when in locked position, and a shoulder on said cam adapted to engage an end of a section and force it circumferentially away from the other section 95 when the lever is actuated to unlock the sections.

3. A demountable rim comprising a plurality of sections connected together for 100 swinging movement inwardly; and means for locking the sections in assembled position as a complete rim, said means including a lever pivotally mounted on an end portion of one of the sections, a cam portion 105 in the lever, said cam being provided with a notch adapted to receive an end portion of a section when in locked position, a shoulder on said cam adapted to engage an end of a section and force it circumferentially away from the other section 110 when the lever is actuated to unlock the sections, and a second shoulder on the cam adapted to engage a portion of the end of one section and force it inwardly radially after 115 said spreading movement.

4. A demountable rim comprising a plurality of sections connected together for swinging movement inwardly; and means for locking the sections in assembled position as a complete rim, said means including a lever pivotally mounted on an end portion of one of the sections, and a cam portion in the lever, said cam being provided with a notch adapted to receive an 120 end portion of a section when in locked position, said cam being disposed on the lever between its pivot-point and an end of a section when assembled.

5. A demountable rim comprising a plu- 130

- rality of sections connected together for swinging movement inwardly; and means for locking the sections in assembled position as a complete rim, said means including a lever pivotally mounted on an end portion of one of the sections, and a cam portion in the lever, said cam being provided with a notch adapted to receive an end portion of a section when in locked position, 5 said lever being also provided with a notch intermediate its ends adapted to receive an edge of one section and initiate a spreading of the sections preparatory to final locking thereof.
- 10 6. A demountable rim comprising a plurality of sections connected together for swinging movement inwardly; a lever pivotally mounted on an end of one section; a cam on said lever in proximity to its pivot-point and adapted to bear on an end of an associated section when the sections are assembled in position; said cam being provided with a notch to permit abutment of the ends of the sections when the lever is forced down into engagement with a section to lock the parts; a rib on the cam to spread the sections circumferentially when the lever is moved in the opposite direction to unlock the parts; and a second rib on 15 the cam adapted to engage a portion of the end of a section and force it inwardly radially after the first rib has initiated the circumferential movement of the sections.
- 20 In testimony whereof I affix my signature in presence of two witnesses.
